COMBINED TOOL BASE AND CUTTER BLOCK FOR A LATHE

Gilbert F. Lutz, Chesterland, Ohio, assignor to The Warner & Swasey Company, Cleveland, Ohio, a corporation of Ohio

Filed Jan. 17, 1966, Ser. No. 638

Term of patent 14 years

(Cl. D54—6)

FIG. 2

FIG. 3

FIG. 4

FIG. 5

FIG. 1 is a front perspective view of a combined tool base and cutter block for a lathe embodying my new design;

FIG. 2 is a top plan view thereof;

FIG. 3 is a front elevational view thereof;

FIG. 4 is a bottom plan view thereof;

FIG. 5 is a side elevational view thereof taken from the left of FIG. 3; and

FIG. 6 is a fragmentary cross-sectional view thereof taken on the line 6—6 of FIG. 5.

The rear not shown is flat and unornamented.

What I claim is:

The ornamental design for a combined tool base and cutter block for a lathe, substantially as shown and described.
